DESIGN FOR A GLASSWARE CLEANING APPARATUS

Vasilios S. Mackres, Brockton, Mass.

Application September 29, 1936, Serial No. 65,044

Term of patent 14 years

To all whom it may concern:

Be it known that I, Vasilios S. Mackres, a citizen of the United States, residing at Brockton, in the county of Plymouth and Commonwealth of Massachusetts, have invented a new, original, and ornamental Design for a Glassware Cleaning Apparatus, of which the following is a specification reference being had to the accompanying drawings, forming a part thereof.

In the accompanying drawings, Figure 1 is a view in right side elevation, of a glassware cleaning apparatus showing my new design, Fig. 2 is a view, in front elevation of the apparatus, and Fig. 3 is a view in plan of the apparatus.

I claim:

The ornamental design for a glassware cleaning apparatus, substantially as shown.

VASILIOS S. MACKRES.
